UNITED STATES PATENT OFFICE

WILLIAM GROSBERG AND GEORGE SUPRENTANT, OF SCHENECTADY, NEW YORK

ATTACHMENT FOR AIR-ESCAPE VALVES

Application filed December 28, 1927. Serial No. 243,139.

The present invention relates to an attachment to the well known air escape valve such as is used on steam heating radiators and the like.

5 The prime object of the invention resides in the provision of an attachment which will cause the ordinary air escape valve to function as a vacuum valve for the purpose of maintaining the heat in the radiator for a 10 longer period of time and to allow the radiator to heat up in a shorter period of time.

A further very important object of the invention resides in the provision of an attachment of this nature which is exceedingly simple in its construction, may be manufactured 15 at an extremely low cost, is easy to mount on the valve, is strong and durable, is compact and convenient, and is thoroughly efficient and reliable in its operation.

20 With the above and numerous other objects in view as will appear as the description proceeds, the invention resides in certain novel features of construction, and in the combination and arrangement of parts as will be 25 hereinafter more fully described and claimed.

In the drawing,

The figure is a sectional view through the attachment showing the same on a conventional form of air escape valve.

30 Referring to the drawing in detail it will be seen that the letter V denotes generally a conventional form of air escape valve now commonly used on steam heating radiators. This valve V comprises a body 5 with a 35 threaded nipple 6 projecting laterally therefrom for engagement in the steam heating radiator in a well known manner. There also projects from the body 5 an externally threaded nipple 7 which rises therefrom and 40 usually threaded receives an apertured cap. Our attachment takes the place of this cap.

45 Referring now in detail to the attachment it will be seen that the numeral 8 denotes a tubular body having an annular flange projecting outwardly from one end as at 9 and beveled as at 10 to fit a like beveled portion on the end of the neck 7. A nut 11 threaded 50ly engages the neck 7 and has a shoulder 12 to engage the flange 9 so that said flange may be held in tight engagement with the end of

the neck. A cup-shaped member 14 has projecting from its bottom a nipple 15 threadedly engaged in the other end of the body 8 and formed with a bore 16 leading into the interior of the cup-shaped member. The inner 55 end of this nipple 15 rises slightly from the bottom of the cup-shaped member interiorly thereof as at 17. A cap 18 is threadedly engaged on the upper end of the cup-shaped member to close said upper end. In the lower 60 corner of the cup shaped member there is provided a diagonal escape opening 19. A disk valve 20 has an elongated stem 21 extending from the center thereof into the bore 16 and this disk valve 20 rests on the projection 17 and closes all communication between the bore 16 and the interior of the cup shaped member 14 normally by gravitation 65 and by vacuum created in the radiator.

70 From the above detailed description it will be seen that when the attachment is first placed on the valve V any air escaping from the valve will lift the disk valve 20 so that the air may escape into the cup-shaped member 14 and out through the opening 19. However, as soon as the steam pressure goes down, 75 atmospheric pressure through the opening 19 and in the cup shaped member 14 will tightly seat the valve 20 on the projection 17 and close all communication between the cup 80 shaped member 14 and the bore 16 so that a vacuum will be formed in the radiator thereby causing the radiator to retain its heat for a greater length of time. It will also be seen that the radiator will heat up more quickly 85 because of the vacuum therein tending to more quickly receive the steam as the pressure rises.

90 It is thought that the construction, utility, and advantages of this invention will be clearly understood without a more detailed description thereof.

The present embodiment of the invention has been disclosed merely by way of example 95 since in actual practice it attains the features of advantage enumerated as desirable in the statement of the invention and the above description. It will be apparent that changes in the details of construction, and in the combination and arrangement of parts may be 100

resorted to without departing from the spirit or scope of the invention as hereinafter claimed, or sacrificing any of its advantages.

Having thus described our invention, what we claim as new is:

5 An attachment for an air escape valve comprising a tubular body, means for attaching one end of the tubular body on the outlet of an air valve, a cup-shaped member having a
10 nipple projecting from the bottom thereof outwardly thereof and threadedly engaged in the other end of the tubular body and provided with a bore, said nipple projecting into the tubular body, a disk valve restable on the
15 nipple in the cup-shaped body, a cap for closing the cup-shaped body, said cup-shaped body being provided with an opening leading through the side thereof immediately adjacent the bottom thereof.

20 In testimony whereof we affix our signatures.

WILLIAM GROSBERG.
GEORGE SURPRENANT.
